DAVIT MECHANISM

Alain de Forest Webster, Glen Cove, N. Y., assignor
to The Landley Company, Inc., New York, N. Y.,
a corporation of New Jersey

Application March 2, 1946, Serial No. 651,570

6 Claims. (Cl. 9—38)

1

The invention aims primarily to provide a davit mechanism having movable parts which may be readily adjusted mechanically between an idle or load stowing position wherein it is nested, so to speak, above the deck, and a load shifting position wherein the boom of the davit projects out beyond the deck as needed to raise or lower a lifeboat or other load. As one feature, the davit is preferably so constructed that during its movement to load stowing position as aforesaid energy is stored up for use in adjusting the movable parts of the davit to load shifting position when desired. Other features and advantages of the invention will be in part obvious and in part specifically referred to in the description hereinafter contained which, taken in conjunction with the accompanying drawings, discloses a preferred form of davit capable of operating in accordance with the invention. The disclosure however should be considered as merely illustrative of the principles of the invention in its broader aspects.

In its preferred form the invention involves the use of a stationary main supporting structure which is secured to the deck, and one or more boom supporting track members which lie adjacent and substantially parallel to the supporting structure when the davit is in load stowing position. In adjusting the davit to load shifting position, these rail members are tilted with respect to the supporting structure so as to assume a position inclined downwardly toward the edge of the deck, and preferably are also shifted bodily with respect to the supporting structure so that their outboard ends project outwardly beyond the deck. The boom of the davit is preferably slideable or rollable along the track members above described, in such manner that the boom is located at the inboard end of the tracks when the latter are in nested or load stowing position, the boom being moved along the tracks out to the outboard projecting ends thereof when the davit is adjusted to load shifting position. Conversely when the davit is adjusted from load shifting to load stowing position, the boom is moved up the incline of the tracks from the outboard to inboard ends thereof, and the tracks themselves are moved inboard and adjusted back to a nested position adjacent and substantially parallel to the supporting structure. Preferably an energy storing mechanism, which may utilize a compression spring, weight, pneumatic pressure cylinder or the like, is so related to the movable parts of the davit that energy is stored therein when the davit is adjusted to load stowing position, so that this energy is available

2

to impart movement to the movable parts of the davit in moving from load stowing to load shifting position. In the drawings—

Fig. 1 is a side elevation of a davit constructed to operate in accordance with the invention, the latter being shown in the position assumed in stowing a lifeboat.

Fig. 2 is a view similar to Fig. 1, but showing the davit in load shifting position.

Fig. 3 is a plan view of the davit, the parts appearing in load stowing position, and certain of them being shown in section.

Figs. 4, 5 and 6 are sectional views taken respectively on the broken lines 4—4, 5—5 and 6—6 of Fig. 3, looking in the direction of the arrows.

Fig. 7 is a general plan view of two of the davits of the type shown in Figs. 1 to 6, said davits being shown in load stowing position and with a lifeboat in stowed relation thereto.

Fig. 8 is a detail section taken parallel to the plane of Figs. 1 and 2, through the boom member of the davit and showing more particularly the details of a locking mechanism which may be used in practicing the invention.

Referring now more specifically to the form of the invention illustrated in the drawings, I have shown a supporting structure consisting primarily of a pair of channel beams 1 and 2 having cross pieces 3 and 4 (Fig. 1) underlying them and resting upon a deck 5, the beams 1 and 2 running crosswise of the deck in such manner that their outer ends are located near the upper side edge 6 of the ship hull.

A pair of track members 7 and 8 shown in the general form of channel beams are mounted between and somewhat above the level of the supporting structure beams 1 and 2. As previously stated these track members 7 and 8 are so mounted with respect to the supporting structure that they may assume a position inclined thereto, and preferably are also bodily movable with respect to the supporting structure to assume either a position wherein their outboard ends project out beyond the hull 6 or a position wherein they are within the confines of the hull. In the illustrated form this is accomplished by providing the beams 1 and 2 at their outer ends with bearing posts 9 and 10 respectively (Fig. 4), in which are journaled rollers 11 and 12 respectively. These rollers 11 and 12 run in elongated guide-ways 13 and 14 respectively on the tracks 7 and 8 so that the track members 7 and 8 may be moved bodily along the supporting structure and may also tilt 55 to the inclined position shown in Fig. 2 in which

their outboard ends project outwardly beyond the hull 6. As shown, the tracks 7 and 8 are connected together by cross braces 8a located underneath them.

Mechanisms are provided to guide the track members 7 and 8 in moving between the positions shown respectively in Figs. 1 and 2, and since the mechanisms used for each track may be the same, a description of one will serve for both. As shown in Figs. 1, 2 and 3, each of such motion guiding mechanisms includes a lever 15 of somewhat H-shape, having its lower ends pivotally connected by a pin 16 to a bearing lug 17 (Figs. 2 and 3) extending up from the supporting structure. At its upper end, each of the levers 15 is pivotally connected by a pin 18 (Fig. 1) to a bearing lug 19 (Fig. 1) extending up from the corresponding tracks 7 or 8 (Figs. 2 and 3). At an intermediate point, lever 15 is pivotally and slidably connected to a thrust rod 20 (Figs. 2 and 3) by means of a pin 21 which works in slots 22 in lever 15 and passes through the adjacent forked end of rod 20 as shown in Fig. 3. As also shown best in this figure, a roller 23 is also journaled on the pin 21. As the track members 7 and 8 move from their load shifting position shown in Fig. 2 to the load stowing position shown in Fig. 1, their corresponding rollers 23 engage with and roll along inclined surfaces 24 of stationary guides which extend up from the supporting beams 1 and 2.

As previously mentioned the davit is preferably provided with devices for absorbing or storing energy as the moving parts move toward the load stowing positions shown in Figs. 1 and 3, in such manner that the energy thus stored may be applied to assist in moving these parts back from load stowing position to load shifting position when next required. In the illustrated form of the invention these energy storing devices take the form of springs which are compressed as the track members move toward the positions shown in Figs. 1 and 3. As shown best in Fig. 3 each of the thrust rods 20 above mentioned works in a cylinder 25 which is pivotally supported at its inner end by pins 26 journaled in brackets 27 extending up from the main supporting beams 1 and 2. A collar 28, fastened to the rod 20, compresses a powerful helical spring 29 as the track members move into the load stowing position shown in Fig. 1, thus storing energy in spring 29. Spring 29 is made powerful enough so that when the moving parts are released for movement toward the load shifting position shown in Fig. 2, as hereinafter described, the energy stored in spring 29 will be sufficient to produce the initial stage of such movement.

As shown in Fig. 3, a positively driven operating mechanism is also provided to produce the above initial movement if spring 29 should fail. For this purpose a screw threaded spindle 30 is provided, about which the rod 20 normally slides freely. As shown in the upper right hand portion of Fig. 3, the threaded spindle 30 may be rotated when desired by a hand crank 31 connected to the spring through appropriate sprocket gearing 32 and bevel gears 33 and 34. An internally threaded nut 35 having a clutched toothed face, is engageable with a hub 36 on the inner end of rod 20 having a complementary clutch toothed face. In case the spring 29 should fail, rod 20 will move far enough to the right (as the parts appear in Fig. 3) for hub 36 to engage with the internally threaded nut 35 above men-

tioned. Then crank handle 31 may be rotated to move the nut 35 to the left as the parts appear in Fig. 3, thus forcing rod 20 to the left and producing the initial movement of the moving parts toward their load shifting position, as a substitute for the stored up energy in the spring which will normally be utilized for this purpose.

A hollow boom member 40 is carried by the tracks or intermediate supporting members 7 and 8, preferably as previously stated in such manner that when the davit is in the load stowing position shown in Fig. 1, the boom 40 is located at the inboard end of track members 7 and 8, and is moved to the outboard end of such track members as the davit is moved to the load shifting position shown in Fig. 2. As shown, the boom 40 is provided with rollers 41 (Fig. 6) located near its inner end and carried by a spindle 42 passing through the boom member, these rollers running within the track members 7 and 8. Similar rollers 43 (Fig. 5) are located at the outer end of the lower portion of boom member 40, these latter rollers being mounted on a spindle 44 which passes through the boom member.

In the form shown the position of the boom member 40, and of the track members 7 and 8 is controlled by the aid of the hoisting mechanism which is used to raise and lower the load with respect to the davit, this hoisting mechanism being operated by an appropriate winch as indicated generally at A in Fig. 7, and being connected to the various parts of the davit by cables and guide sheaves as now to be described. As shown best in Fig. 3 the hoist cable 45 is anchored at one end by a turn-buckle 46 to the track member 8. From this point, cable 45 passes under a sheave 47a located part way up the boom member, and from thence over further sheaves 47 and 48 at the overhanging upper end of the boom member. From thence, cable 45 passes around under a further sheave 49 (Fig. 3) constituting part of the tackle block 50 which carries the load, then over a further sheave 51 at the outer end of the boom on the opposite side thereof with respect to sheave 48. Then cable 45 passes over a further sheave 52 which is on the opposite side of the boom from sheave 47, and then around a further sheave 53 lower down on the boom, which is opposite a sheave 47a. From sheave 53, cable 45 passes to a sheave 54 on rail member 7, and then around a sheave 54a (see Fig. 5) on the rail member 7, from whence cable 45 passes to a further sheave 55 (Fig. 5) mounted in a bracket 56 extending up from the supporting beam 1. Then the cable passes around a sheave 57 (Fig. 3) which may be appropriately supported from any convenient part of the stationary structure, after which the cable 45 passes to the winch as indicated in Fig. 7. This figure shows two hoisting cables 45 and 45a leading to the two davits which are located respectively at the opposite ends of the lifeboat.

If it be assumed that the davits and load to be stowed are in position shown in Fig. 2, winding up of the winch A will continue to lift the load until tackle block 50 comes up against the overhanging outer end of boom member 40. Then further tension on cable 45 will cause the portion thereof which passes around the sheaves on boom member 40 to shorten up, thus moving boom member 40 from the full line position shown at the left of Fig. 2, to the dotted line position indicated at the inner end of track 7. Further tension on cable 45 will cause the portion thereof which is between the sheaves

54a and 55 to shorten up, thus withdrawing the tracks 7 and 8 from the overhanging position shown in Fig. 2, to a position wherein (as the parts appear in Fig. 1), the roller 41 engages the left hand end of guideway 13. During this stage the tracks 7 and 8 will swing partially down toward the position shown in Fig. 1. Further tension on the cable 45 thereupon swings the inner ends of tracks 7 and 8 downwardly about rollers 41 and 42 as pivots, fully into the position shown in Fig. 1.

During the above described retracting movement of tracks 7 and 8, the levers 15 swing to the right from the position shown in Fig. 2, about pins 16 as pivots, and this movement forces the rods 20 further into cylinders 25, thus compressing the springs 29 within such cylinders, and storing energy therein. Then during the final angular movement of track members 7 and 8 down to the position shown in Fig. 1, the levers 15 are swung further downwardly, thus fully compressing the springs 29 in cylinders 25.

As shown in Figs. 1 and 2 the track members 7 and 8 may be provided with shoulders 60 which are engaged by the keel of a lifeboat as the boom member 43 moves toward its load stowing position, thus causing the lifeboat to tilt inwardly as shown in Fig. 1 as the davit assumes final load stowing position. In final stowed position the lifeboat may rest upon cradles 61 as best shown in Figs. 2 and 7, being preferably lashed in this position as is well known in the art and accordingly need not be described herein in detail.

When the lifeboat or other load is to be launched or unloaded, tension on the cables 45 and 45a is slackened off gradually, and the springs in cylinders 25 are made powerful enough as above described so that the energy stored therein is sufficient to tilt the tracks up to inclined position. Further easing off in the tension on cables 45 and 45a causes the boom to slide down tracks 7 and 8 to the outboard position shown in Fig. 2, assisted by the weight of the load itself. Still further slackening of cable 45 causes the load to be lowered from boom 40.

Preferably a locking mechanism is provided for the boom 40, which may be actuated when the boom and track members are in the load shifting position shown in Fig. 2 to prevent the boom from moving up the incline of the tracks until the load or the tackle block 50 which carries the load, has been hoisted fully up to the overhanging outer end of boom 4. In the illustrated form of the invention this locking mechanism is automatic in its action, and includes a roller 62 (Fig. 8) at the lower outer end of boom 40, which roller is mounted in a link 63 pivoted within the boom at pin 64. Except when boom member 40 is at the outer limit of its path of travel, roller 62 rides over the top of a guide rail 65 located between the track members 7 and 8. A further link 63 within boom member 40 is also connected at its lower end to roller 62, and at its upper end to a bell crank lever 67, which latter is in turn connected to a link 68 pivotally connected to links 70 and 71. Link 70 is pivoted about pin 72 and link 71 is pivotally connected to the end of a forked dog 73 which is pivoted about pin 74 which also carries sheaves 48 and 51. The upper end of the tackle block 50 may be provided with an upper cross bar 75 (Fig. 8) which moves dog 73 anti-clockwise from the position shown in full lines in Fig. 8 when the load is lowered. This movement will cause the roller 62 to move down to locking position with

respect to a shoulder 76 at the outer end of rail 65, thus preventing the boom from moving up the incline of the tracks so long as the load is being lowered. This locked condition persists until the load, or tackle block 50, has been fully raised, at which stage the cross bar 75 moves dog 73 clockwise to the position shown in full lines in Fig. 8, thus raising roller 62 out of locking engagement with shoulder 76. Thereupon, the load being fully raised, the boom member and the load may be pulled up the incline of tracks 7 and 8 by further tightening up on the hoist cables, and the tracks moved angularly to load stowing position, as above described.

16 A construction of the above type occupies relatively small head room, since the movable parts nest closely down toward the deck when the davit is in load stowing position, but may be readily tilted to load shifting position when required.

20 While the invention has been disclosed as carried out by davits of the above described specific construction, it should be understood that many changes may be made therein without departing from the invention in its broader 25 aspects, within the scope of the appended claims.

I claim:

30 1. A davit of the character described including a supporting structure, an intermediate boom supporting member carried by said supporting structure, and mounted thereon for angular movement between a load stowing position wherein it lies adjacent said supporting structure and a load shifting position wherein it is relatively more inclined to said supporting structure, 35 a boom member carried by said intermediate supporting member, a rocking lever connected to said intermediate boom supporting member to guide its angular movements aforesaid, and compression spring means connected with said lever 40 to store up energy in said spring when said intermediate supporting member moves from its second to its first above mentioned position and apply the thus stored energy to said lever as said intermediate supporting member moves from its first to its second above mentioned position.

45 2. A davit of the character described including a supporting structure, an intermediate boom supporting member carried by said supporting structure, and mounted thereon for movement between a load stowing position and a load shifting position wherein it is relatively more inclined to said supporting structure, means connected to the inboard portion of said intermediate member for moving the latter upwardly to load shifting position, a boom member carried by said intermediate supporting member, energy storing mechanism energized by movement of said intermediate supporting member to load storing position, load lifting and lowering mechanism operating to move said intermediate supporting member from its second to its first above mentioned position, said energy storing mechanism being connected to said intermediate member moving means.

55 3. A davit of the character described including a supporting structure constructed to be mounted on a deck, a rail member having its outer end portion tiltably engaged with said supporting structure at a point adjacent the edge of said deck, 60 said rail member when in load stowing position lying substantially parallel to and adjacent said deck throughout the length of the rail member, mechanism connected to the inboard portion of said rail member for moving the latter upwardly 65 to a load shifting position wherein the rail mem-

ber inclines downwardly toward the edge of the deck, a boom member carried by said rail member, load lifting and lowering mechanism including sheave members mounted on said boom and rail members, and cable means guided by said sheaves, an energy storing device connected to said first mentioned mechanism to store up energy in said device upon movement of said first mentioned mechanism from load shifting to load stowing position, said load lifting and lowering mechanism operating to move the boom member and the rail member from load shifting to load stowing position, thereby to store energy in said device to move said first mentioned mechanism and said rail and boom members upwardly from the load stowing to load shifting position.

4. A davit of the character described including a supporting structure constructed to be mounted on a deck, a rail member having its outer end portion tiltably engaged with said supporting structure at a point adjacent the edge of said deck, said rail member when in load stowing position lying substantially parallel to and adjacent said deck throughout the length of the rail member, mechanism connected to the inboard portion of said rail member for moving the latter upwardly to a load shifting position wherein the rail member inclines downwardly toward the edge of the deck, a boom member slidably carried by said rail member to afford movement between an inner load stowing position and an outer load shifting position, load lifting and lowering mechanism including sheave members mounted on said boom and rail members and cable means guided by said sheaves, said last mentioned mechanism operating to move the rail member from load shifting to load stowing position and to slide said boom member from outer to inner position with respect to said rail member.

5. A davit of the character described including a supporting structure constructed to be mounted on a deck, a rail member having its outer end portion tiltably engaged with said supporting structure at a point adjacent the edge of said deck and being also slidably engaged with said supporting structure to afford movement of said rail member between an inner load stowing position and an outer load shifting position, said rail member when in load stowing position lying substantially parallel to and adjacent said deck throughout the

length of the rail member, mechanism connected to the inboard portion of said rail member for moving the latter upwardly to a load shifting position wherein the rail member inclines downwardly toward the edge of the deck and shifting said rail member to its aforesaid outer position, a boom member carried by said rail member, load lifting and lowering mechanism including sheave members mounted on said boom and rail members and cable means guided by said sheaves, said last mentioned mechanism operating to move the boom and rail members from their aforesaid load shifting to load stowing position.

6. A davit of the character described including a supporting structure constructed to be mounted on a deck, a rail member having its outer end portion tiltably engaged with said supporting structure at a point adjacent the edge of said deck, said rail member when in load stowing position lying substantially parallel to and adjacent said deck throughout the length of the rail member, a lever mechanism connected to the inboard portion of said rail member for moving the latter upwardly to a load shifting position wherein the rail member inclines downwardly toward the edge of the deck, and a spring mechanism connected to said lever mechanism to store up energy in said spring as the rail member moves from load shifting to load stowing position, a boom member carried by said rail member, and cable and sheave means for shifting said boom and rail members from load shifting to load stowing position.
